No. 857,669.

PATENTED JUNE 25, 1907.

J. F. A. PROBST.
FAN ATTACHMENT FOR CHAIRS.

APPLICATION FILED SEPT. 8, 1905.

UNITED STATES PATENT OFFICE.

JOSEPH F. A. PROBST, OF SHARPSBURG, PENNSYLVANIA.

FAN ATTACHMENT FOR CHAIRS.

No. 857,669.

Specification of Letters Patent.

Patented June 25, 1907.

Application filed September 8, 1905. Serial No. 277,559.

To all whom it may concern:

Be it known that I, JOSEPH F. A. PROBST, a citizen of the United States of America, residing at Sharpsburg, in the county of Allegheny and State of Pennsylvania, have invented certain new and useful Improvements in Fan Attachments for Chairs, of which the following is a specification, reference being had therein to the accompanying drawing.

This invention relates to new and useful improvements in fan attachments for rocking chairs.

The particular construction contemplates a device embodying a rotatable rod which is reciprocated vertically on each rocking movement of the chair, and which is automatically returned to initial position without the provision of any extraneous mechanism theretofore. These functions are accomplished by the detailed construction which will appear as the description proceeds, reference being had therein to the accompanying drawings forming a part of this specification, like numerals indicating like parts throughout the several views in which:—

Figure 1 is a side elevation, one of the rockers being broken away to show the construction of the lower portion of the fan operating attachment, Fig. 2 is a detailed sectional view enlarged of a hinged swivel joint connecting the rod above referred to to a base shown in elevation, Fig. 3 is a side elevation enlarged of a collar sleeved upon said rod and a clamp for holding said collar to the chair, Fig. 4 is a top plan view thereof, Fig. 5 is a longitudinal section enlarged showing the interior construction of the collar. Fig. 6 is a side elevation of a clamp connecting the structure at its face with the rocker of the chair, and Fig. 7 is a top plan view thereof. Fig. 8 is a top plan view enlarged of the fan, the ends thereof being broken away, and showing a ratchet device for preventing the backward rotation thereof. Fig. 9 is a side view of the parts shown in Fig. 8.

Referring specifically to the accompanying drawings A designates a rocking chair which is provided with the usual curved rockers B of ordinary form. The fan attachment therefor embodies a vertical rod 1 which is provided adjacent the upper portion thereof with a relatively long spirally threaded surface 2. The rod 1 is formed on its lower end with a head 3, see Fig. 2 which is rotatably mounted in a socket 4, a set screw 5 being

threaded into said socket and being adapted to engage an annular groove 6 formed on said rod 1 adjacent the head 3 thereof, to prevent the displacement of the said rod. The 60 socket 4 is hinged by a knuckle joint 7 to a base 8 carrying a friction roller 9. The base 8 has rigid connection in any desirable manner with a very powerful leaf spring 10 by which it is connected to the rocker B, the 65 said spring 10 having its other end secured to a lateral extension 11 mounted upon a U shaped clamp 12, adapted to straddle said rocker and be held thereon by a flat headed set screw 13. The rod 1 is connected to the 70 back of the chair A at its top by virtue of a clamp 14 similar in construction to the clamp 12. The clamp 14 carries a hinged socket 15 into which is threaded a set screw 16 which secures in said socket a rod 17 having a terminal collar 18, sleeved upon said rod 1. The collar 18 is shown in detail in Fig. 5, and is formed with a vertical bore 19 into which projects short length inclined teeth 20, adapted to mesh with the spirally 80 threaded surface 2 of said rod 1.

The fan 21 carries on its under surface, at its center, a depending socket 22 which is held on the rod 1 by a set screw 23, and the fan is free to revolve on the socket. Fan 21 85 has mounted thereon a spring pressed pawl 24, adapted to engage with the teeth of a ratchet 25 integral with the socket 22. It should be here stated that the socket 22 is loosely mounted on said fan 21 so as to have 90 rotation independent thereof. Revolubly mounted upon the socket 22 is a finger 26 which is bent into an L shape and projects through a curved slot 27 in the fan blade 21, the pin 26 being adapted to engage the 95 curved surface of the pivoted pawl 24 so as to throw the latter, at the proper time, out of engagement with the ratchet 25.

In operation as the chair is rocked, on the backward stroke of the rockers B, the rod 1 100 will hit the floor against the tension of the spring 10, the roller 9 upon the base thereof, affording an even surface of travel. The movement of the chair upon its rockers will cause the sleeve 18 to also move in a vertical 105 direction on the rod, and the latter will be simultaneously rotated through the intermeshing engagement of the teeth 20 formed in the bore 19 of the collar 18 with the spirally threaded surface 2 of said rod. As 110 the rod is rotated it will engage the pawl 24 with its ratchet 25 of the fan 21 and posi-

tively move the latter. When the backward movement of the rocker ceases and the forward movement thereof commences, the spring 10 will maintain said rod 1 in engagement with the floor until the chair moves forward far enough to relieve the tension of the spring, and thereby as the sleeve 18 moves upward and backward with the rocker, the rod 1 will be alternately rotated in opposite directions. As the rotary motion of the rod 1 ceases, the momentum of the fan 21 will continue its rotation and overtake the upward projecting portion of the rod 26 and cause the same to act upon the inclined outer end of the pawl 24 and disconnect the latter from the ratchet and permit the rod to return to its former position, and when the next forward stroke commences the momentum of the fan will release the rod 26 and permit the pawl to be again thrown in contact with the ratchet ready to repeat the stroke. By this means the forward motion of the fan is continuous as will be obvious.

Various minor changes may be made without departing from the spirit or scope of my invention as defined in the appended claims.

Having fully described my invention, I claim:

1. A fan attachment for rocking chairs embodying a substantially vertically disposed rod, a spring secured to said rod adjacent to bottom thereof and a clamp carried by said spring whereby to secure the latter to the rocker of a chair said rod being formed for a portion of its length with a threaded surface, a collar sleeved upon said rod, said collar having pivotal connection with a clamp mounted upon the back of the chair, said collar being also internally threaded and

adapted to engage with the rod threads, a fan, a depending socket loosely mounted therein, means for securing said socket to said rod, a ratchet carried by said socket, a spring pressed pawl carried by said fan blade and adapted to be engaged by said ratchet, and a resilient finger projecting through a slot in said fan and movable therein, said finger being adapted to engage said pawl to throw the latter away from contact with said ratchet.

2. A fan attachment for rocking chairs embodying a vertical rod formed along a portion of its length with a threaded surface, a socket secured to the bottom of said rod, a friction roller mounted in said socket, a leaf spring rigidly carried by said socket, a clamp rigidly secured to the end of the said leaf spring and adapted to straddle the rocker of the chair whereby to secure said leaf spring to said rocker, a clamp secured to the back of the chair, a hinge socket carried by said clamp, a stationary collar sleeved upon said rod and held in said socket, said collar being formed on its inner periphery with inclined teeth adapted to intermesh with said spiral surface, a fan, a depending socket rotatably mounted in said fan at a central point, means for securing the said socket to said rod, a ratchet carried by said socket and a spring pressed pawl pivotally mounted upon said fan and adapted to be engaged by said ratchet.

In testimony whereof I affix my signature in the presence of two witnesses.

JOSEPH F. A. PROBST.
